HOLDER FOR COCKTAIL OLIVES AND THE LIKE

James H. Ogg, North Hollywood, Calif., assignor to Zoo-Piks, Inc., a corporation of California

Filed Jan. 4, 1963, Ser. No. 73,050

Term of patent 14 years

(Cl. D44—29)

FIG. 1.

FIG. 2.

FIG. 3.

FIG. 4.

I claim:

The ornamental design for a holder for cocktail olives and the like, substantially as shown.
